DESIGN FOR A BOTTLE NIPPLE

Nat P. Steckler, New York, N. Y.

Application August 27, 1936, Serial No. 64,589

Term of patent 14 years

To all whom it may concern:

Be it known that I, Nat P. Steckler, a citizen of the United States, residing at New York, in the county of New York and State of New York, have invented a new, original, and ornamental Design for a Bottle Nipple, of which the following is a specification, reference being had to the accompanying drawing, forming part thereof.

The characteristic feature of my design resides in a nipple of the configuration shown, having four vertical ribs, uniformly spaced circum-

ferentially and substantially midway between the two ends of the nipple, and an ornamental band consisting of star figures arranged immediately under the lower end of the vertical ribs.

In the drawing:

Fig. 1 is a top plan view of a bottle nipple, showing my new design.

Fig. 2 is a front elevation thereof.

I claim:

The ornamental design for a bottle nipple, as shown and described.

NAT P. STECKLER.
